HAROLD T. ZULAWINSKI, OF PORTLAND, OREGON

SPARK PLUG

Application filed May 2, 1928. Serial No. 274,393.

This invention relates generally to internal combustion engines, and particularly to spark plugs such as are commonly used in connection therewith.

5 The main object of this invention is to construct a spark plug which will be self-cleaning and which will not become short circuited due to fouling.

10 The second object is to construct a plug having an intense spark which occurs within a recess formed in the porcelain shell of the plug.

15 The third object is to design a plug which will be easy to construct and not liable to get out of order on account of delicate or fragile parts.

20 The fourth object is to so construct the plug that any oil reaching the central electrode will run to its pointed end where it will be burned off or drip therefrom, and any oil which reaches the ground electrode will run to that portion of the electrode subjected to the heat of the combustion and to the rapidly passing gases, which will separate it from the electrode, and in any event it can never collect on that portion of the ground electrodes where the sparking occurs.

25 The fifth object is to so construct the end of the spark plug body that it will afford the minimum amount of lodgment for carbon, and that any carbon which is deposited on same can be easily removed therefrom on account of the shape of the plug end.

30 These, and other objects, will become more apparent from the specification following as illustrated in the accompanying drawing, in which:

35 Figure 1 is a side elevation of the plug showing same mounted on the cylinder head which is shown in section. Figure 2 is a vertical section through the plug. Figure 3 is a bottom view of the plug. Figure 4 is a perspective view of the bottom or firing end of the plug. Figure 5 is a fragmentary section taken along the line 5—5 in Figure 3.

40 Similar numbers of reference refer to similar parts throughout the several views.

45 Referring in detail to the drawing, the plug itself consists of a body 10 whose end 11 is threaded and whose opposite end 12 is hex-

agonal in shape for the purpose of receiving a wrench, while the middle 13 is flanged to engage the gasket 14. The tip 15 of the body 10 is chamfered to reduce the area on which carbon can accumulate, as well as to reduce the tendency toward such accumulation. On opposite sides of the tip 15 are formed the projections 16 in each of which is mounted a U-shaped ground electrode 17 whose upper ends 18 extend above the bottom line 19 of the plug body 10.

50 The interior of the body 10 is counterbored within the hexagonal portion 12, and the outermost portion of the counterbore is threaded to receive the nut 20. Within the body 10 is placed a porcelain core or shell 21 provided with a central flange 22, on each side of which is placed a gasket 23, which gaskets are held firmly in position by the nut 20.

55 One end 24 of the core 21 extends to the bottom line 19 of the body 10 and is provided with a hemispherical recess 25. A central electrode 26 passes axially through the core 21 and its pointed end 27 reaches approximately to the line 19 and lies between the ends 18 of the ground electrodes 17. The opposite end of the core 21 has mounted thereon a metal cap 28 through which projects the electrode 26 whose outer end 29 is threaded to receive the clamping nuts 30 for the ignition wires.

60 In operation the plug is used in the same manner as is the usual type of spark plug but, due to the fact that the sparking occurs within the recess 25, this portion of the plug is always free from carbon, and, owing to its shape, is always accessible for cleansing purposes without the necessity of taking the plug apart with the attendant possibility of changing the adjustment thereof.

65 It is a well known fact that many types of spark plugs have been constructed in the past; it is therefore not my intention to cover such devices broadly, but I do intend to cover all such forms and modifications thereof as fall fairly within the appended claim.

70 I claim:

75 A spark plug the combination of a body having one of its ends threaded for mounting in a cylinder head, the extreme end of

said plug which enters said cylinder head having a chamfered face, a porcelain core mounted in said body extending to the tip of said chamfered face, the end of said core nearest said chamfered face having a recess formed therein, an electrode mounted in said core having a pointed end projecting into said recess, and a pair of U-shaped ground electrodes one side of each of which is mounted 5 in said body and the other side projecting into said recess, the middle portions of said ground electrodes curving beyond the outer limits of the plug, the spark gap formed by said electrodes lying relatively within said 10 recess.

HAROLD T. ZULAWINSKI.
